US00D444453S

(12) **United States Design Patent** (10) Patent No.: **US D444,453 S**
Stroede et al. (45) Date of Patent: ** Jul. 3, 2001

(54) **WIRE CONTAINMENT FOR MODULAR CONNECTOR**

(75) Inventors: **Andrew J. Stroede**, Mokena; **Russell A. Vanderhoof**, Minooka; **Michael Doorhy**, Tinley Park, all of IL (US)

(73) Assignee: **Panduit Corp.**, Tinley Park, IL (US)

(**) Term: **14 Years**

(21) Appl. No.: **29/109,312**

(22) Filed: **Aug. 12, 1999**

(51) LOC (7) Cl. **13-03**

(52) U.S. Cl. **D13/154**

(58) Field of Search **D13/147, 146, D13/154; 439/417, 686, 695, 701, 712, 724, 752**

(57) **CLAIM**

The ornamental design for a wire containment for modular connector, as shown and described.

DESCRIPTION

FIG. 1 is a front perspective view of a wire containment for modular connector showing our new design;

FIG. 2 is a rear perspective view of a wire containment for modular connector showing our new design;

FIG. 3 is a bottom and front perspective view of a wire containment for modular connector showing our new design;

FIG. 4 is a front elevational view thereof;

FIG. 5 is a rear elevational view thereof;

FIG. 6 is a side elevational view thereof;

FIG. 7 is the opposite side elevational view thereof;

FIG. 8 is a top plan view thereof; and,

FIG. 9 is a bottom plan view thereof.
